UNITED STATES PATENT OFFICE.

CHARLES P. ANDERSON, OF ST. LOUIS, MISSOURI.

GUARD FOR INCANDESCENT ELECTRIC LAMPS.

No. 797,250.

Specification of Letters Patent.

Patented Aug. 15, 1905.

Application filed March 17, 1905. Serial No. 250,673.

To all whom it may concern:

Be it known that I, CHARLES P. ANDERSON, a citizen of the United States, residing in the city of St. Louis, in the State of Missouri, have invented certain new and useful Improvements in Guards for Incandescent Electric Lamps, of which the following is a full, clear, and exact description, reference being had to the accompanying drawings, forming part of this specification.

My invention relates to a guard for protecting the bulbs of incandescent electric lamps and preventing breakage thereof by contact with any object toward which the lamp may be moved while hanging suspended and also whereby excessive vibration of the lamp-bulb is avoided.

Figure I is a perspective view of my lamp-guard. Fig. II is a view of the socket of a lamp with the upper end of my guard applied thereto and shown in vertical section. Fig. III is a cross-section through the ends of the clamp-band of the guard. Fig. IV is a cross-section through a portion of the guard, as seen in Fig. I. Fig. V is a cross-section through a modification of my guard. Fig. VI is a perspective view of a portion of the wires in the modified form of guard shown in Fig. V. Fig. VII is a cross-section of another modification.

1 designates a plurality of longitudinal main wires of my guard, which are disposed in a circle and are inclined inwardly from vertexes 2 intermediate of the ends of the guard, so that the circle of the guard is greater at a point intermediate of the ends of the guard than the circles at the ends of the guard. At the angles formed by the vertexes of the wires 1 is located a spreading-ring 3, through which the wires 1 are threaded. This spreading-ring being located at the point mentioned is held from movement longitudinally of the guard upon the wires, due to the wires being inclined inwardly in each direction therefrom, and therefore the spreading-ring will maintain its position without any securing means, although, if desired, the ring may be soldered to the wires.

4 is a lower ring through which the lower ends of the longitudinal wires 1 are threaded and secured by having their ends bent around said ring, as seen in Fig. I. This lower ring is of sufficient interior diameter to permit of a lamp-bulb being passed therethrough to have its neck seated in the lamp-socket with-

out the necessity of removing the guard from the socket to which it is fitted in the manner to be presently explained.

5 designates a clamping-band having ends 6 and 7, through which a screw 8 is inserted, the end 7 being of loop form and tapped for the reception of the threaded end of said screw, thereby affording greater bearing for the screw when it is introduced into the band. The upper ends of the longitudinal wires 1 are threaded through the band 5, and the terminations 1^a of the wires are bent downwardly at the interior of the band, as seen in Figs. I and II. These terminations are thereby disposed in a circle within the band in a position to bear against the neck A of the lamp-socket and their lower points by engaging against the usual bead B upon the socket-neck serves to effectually hold the clamp-ring from movement on the socket after it has been applied thereto. It will be seen that by the construction described the terminations of the longitudinal wires may be made to fit above the socket-bead irrespective of the degree of space surrounding the socket above the bead to which a clamping-band may be applied.

9 designates a cushion-supporting ring located interior of the spreading-ring 3 and concentric therewith, the said ring 9 being secured to the spreading-ring by arms 10, extending outwardly from the ring 9 and secured to the spreading-ring.

11 is a coiled cushion mounted upon the ring 9 and which is adapted to surround and bear against the portion of the lamp-bulb of greatest diameter, whereby vibration is effectually prevented. To this end it is necessary that the coiled cushion be located around the lower portion of the bulb, which is that having the greatest diameter. The cushion-spring is also of material utility in avoiding sudden jar to the lamp-bulb due to the guard coming in contact with any object.

It will be seen that in the use of a guard constructed in accordance with my improvement the guard may be applied to a lamp-socket and thereafter lamp-bulbs may be introduced into and withdrawn from the lamp-socket without any necessity whatever of removal of the guard, this being due to the lower ring 4 of the guard being of sufficient diameter to permit of the lamp-bulb being freely passed therethrough for introduction into the socket and withdrawal therefrom. By this arrangement I avoid any manipulation of the

guard and obviate the danger of the guard being taken off and lost or displaced when a new lamp is to be put into the socket and also avoid making the guard in sections to permit of its being opened to insert and remove the lamp-bulbs.

In Figs. V and VI, I have shown a modification in which the longitudinal wires 1^b are of the same configuration as the wires 1. In this modification, however, I utilize a spreading-ring 3^b, that is indented at intervals to receive the longitudinal wires instead of threading the wires through the ring. The lower ring 4^b is also indented at intervals to receive the connection of the lower ends of the longitudinal wires instead of threading them therethrough. In this modification I utilize a cushion-ring 11^b, that is of rectangular shape and which is wrapped around the spreading-ring 3^b at the junctions of the longitudinal wires therewith, as seen in Fig. V, this ring being adapted to bear directly against the lamp-bulb in lieu of the coiled cushion 11.

In Fig. VII, I have shown another modification in which the spreading-ring 3^c is of twisted form and the longitudinal wires 1^c are threaded through eyes in said ring. This modification corresponds otherwise to the modification shown in Figs. V and VI in having a lower ring 4^b, to which the longitudinal

wires are secured, and the rectangular cushion-ring 11^b.

I claim as my invention—

1. The combination with an incandescent-electric-lamp socket provided with a circumferential bead, of a guard having longitudinal wires, a clamp-band through which said longitudinal wires are threaded; the terminations of said wires being bent after passing through said clamp-band and adapted to engage said socket-bead when the clamp-band is fitted to said socket, substantially as and for the purpose set forth.

2. In an incandescent-lamp guard, the combination of a plurality of longitudinal wires disposed in a circle, a clamp-band for securing said wires to a lamp-socket, a continuous spreading-ring interposed between the ends of said wires and to which the wires are fitted, a continuous cushion-supporting ring secured to said spreading-ring, and a continuous coiled cushion surrounding said supporting-ring and arranged to bear against the lower end of the lamp-bulb, whereby the lamp-bulb is held from vibration, substantially as and for the purpose set forth.

CHAS. P. ANDERSON.
